UNITED STATES PATENT OFFICE.

SILAS W. BENNETT, OF SOMERVILLE, MASSACHUSETTS, ASSIGNOR OF ONE-HALF TO ELMER N. HUTCHINS, OF SOMERVILLE, MASSACHUSETTS.

SUPPORTING AND STRETCHING DEVICE FOR WOVEN-WIRE SPRINGS.

No. 916,655.

Specification of Letters Patent. Patented March 30, 1909.

Application filed November 5, 1908. Serial No. 461,181.

To all whom it may concern:

Be it known that I, SILAS W. BENNETT, a citizen of the United States, residing at Somerville, in the county of Middlesex and 5 State of Massachusetts, have invented certain new and useful Improvements in Supporting and Stretching Devices for Woven-Wire Springs; and I do declare the following to be a full, clear, and exact description 10 of the invention, such as will enable others skilled in the art to which it appertains to make and use the same.

This invention relates to improvements in bed-spring supports and stretchers.

15 The object of the invention is to provide a device of this character by means of which woven wire springs may be secured to bedsteads, couches and the like, and by means of which the springs may be stretched 20 and tightened to take up the sag therein.

With this and other objects in view, the invention consists of certain novel features of construction, combination and arrangement of parts as will be described and particularly pointed out in the appended 25 claim.

In the accompanying drawing, Figure 1 is a plan view of a bed-steal showing the application of the device thereto; Fig. 2 is a 30 side view of the same; Fig. 3 is an enlarged sectional view through one of the side rails of the bed showing one of the bearing brackets and one end of the winding roll engaged therewith; Fig. 4 is a vertical longitudinal sectional view through the parts shown in Fig. 3 taken on the line 4—4 of Fig. 2; Fig. 5 is a detail perspective view 35 of a modified form of bracket and means for fastening the same to the bed-rail.

40 In the embodiment of the invention I provide a plurality of bearing brackets, 1, one of which is secured to the head end of each of the side rails of the bed or couch frame. The bearing brackets shown in the first 45 four figures of the drawings comprise a base or rail-engaging portion, 2, said base having on its inner edge a downwardly and inwardly projecting flange, 3, which is adapted to engage the under side of the angle-iron rails of the bed. The base, 2, and flange, 3, are provided with a centrally-disposed strengthening web or brace, 4. In the flange, 3, is formed a centrally disposed enlargement or boss, 5, in which is formed 55 a threaded passage, 6, to receive a set screw,

7, adapted to be screwed into engagement with the under side of the bed rail whereby the bracket is adjustably held in position thereon. The bracket, 1, extends upwardly and projects at an incline beyond one end 60 of the base, 2, and on the upper end of the bracket is formed a bearing head, 8, provided with a bearing aperture, 9, having in its edge a series of radially-disposed locking notches, 10, the purpose of which will 65 hereinafter appear.

Revolubly mounted in the bearing apertures, 9, of the brackets are winding cylinders, 12, said cylinders having adjacent to one end an annular flange, 13, which, when 70 the cylinder is in place, engages the inner side of the bearing heads, 8, of the bracket and forms a stop to limit the outward movement of the cylinder. In the outer end of each of the cylinders, 12, is formed a square 75 or rectangular socket, 14, adapted to receive the end of a wrench or crank, 15, by means of which the cylinders are revolved. At diametrically opposite points in the outer ends of each of the cylinders are formed 80 locking notches, 16, which are adapted to be brought into alignment with the locking notches, 10, in the bearing head, 8, of the brackets, and into the aligned notches in said head and cylinders are inserted locking pins 85 or keys, 17, whereby the cylinders are locked against rotation in the brackets. Through the inner portion of each of the bearing cylinders is formed a transversely disposed 90 elongated passage, 18.

The inner portions of the cylinders, 12, are adapted to be engaged with the ends of a tubular winding roll, 19, which is arranged at the head end of the bed or couch. The ends of the roll, 19, are secured to the 95 cylinders by means of transversely disposed fastening bolts, 20, which are inserted through apertures in the ends of the roll and through the elongated passages, 18, in the cylinders. To the winding roll is secured 100 the forward end of a woven wire spring which extends from one end of the bedstead to the other in the usual manner, and is connected at its rear end to an angle-iron cross bar, 19', the ends of which are secured in 105 the heads 8' of brackets, 1', which are similar in construction to the brackets, 1, at the head end of the bed, except that the heads, 8', are adapted to receive the ends of the bar, 19', instead of the cylinder, 12. 110

When the parts are arranged as herein described, the forward end of the spring may be wound upon the roll, 19, by the application of a wrench to the winding cylinder 12, 5 thereby stretching and tightening the spring to the desired degree, after which one or more locking pins, 17, are engaged with the alined notches in the cylinders and bearing bracket, thereby locking the winding cylinders and roll against a retrograde movement 10 and holding the spring stretched.

In the form of device shown in Fig. 5 of the drawing the bracket consists of a bearing head, 21, having a bearing aperture, 22, 15 and locking notches, 23. The inner end of the bracket is provided with a tapered or wedge-shaped shank, 24, having a flat rail-engaging surface, 25, adapted to rest upon the upper side of the rails of the bed or couch frame. The shank, 24, of the bracket is securely fastened to the side rail by means of a clamping block, 26, having a shank-engaging portion, 27, on the inner edge of which is formed a downwardly and inwardly-projecting right-angular flange, 28, 20 which is adapted to engage the under side of the rail as clearly shown in dotted lines in Fig. 5. On the outer edge of the shank engaging portion, 26, is formed a right-angularly projecting rail-engaging portion, 29, on the lower edge of which is formed an inwardly and upwardly projecting rail-engaging flange, 30, which is provided with an inclined upper edge and is adapted to grip 25 the lower edge of the rail, as shown. When the clamping block is engaged with the rail and wedge-shaped shank of the bracket, the latter will be securely held in operative engagement with the rail by the tapered or

wedge-shaped construction of the shank. 40 By this construction, the greater the strain applied to the bracket, the more tightly will the same be gripped and secured to the rail.

From the foregoing description, taken in connection with the accompanying drawing, 45 the construction and operation of the invention will be readily understood without requiring a more extended explanation.

Various changes in the form, proportion and the minor details of construction may 50 be resorted to without departing from the principle or sacrificing any of the advantages of the invention as defined in the appended claim.

Having this described my invention, what 55 I claim as new and desire to secure by Letters-Patent, is:

In a device of the class described, a series of roller supporting brackets slidably and adjustably mounted upon the side rails of 60 the bed, a spring winding roller, winding cylinders having their inner ends fitting in the ends of the winding cylinders, said ends of the winding cylinders having a slotted connection with the winding roller whereby 65 the former may be adjusted longitudinally, the outer ends of the winding cylinders extending through the bearing brackets, and means to key the outer ends of the winding cylinders to said brackets. 70

In testimony whereof I have hereunto set my hand in presence of two subscribing witnesses.

SILAS W. BENNETT.
